UNITED STATES PATENT OFFICE.

DAVID LENNOX, OF MARSHALLTOWN, IOWA.

PLATFORM-SCALE.

No. 901,356.

Specification of Letters Patent.

Patented Oct. 20, 1908.

Application filed May 11, 1907. Serial No. 373,034.

To all whom it may concern:

Be it known that I, DAVID LENNOX, a citizen of the United States of America, and a resident of Marshalltown, Marshall county, 5 Iowa, have invented certain new and useful Improvements in Platform-Scales, of which the following is a specification.

My invention relates to improvements in weighing scales, and the object of my improvement is to provide improved frictionless corner bearings for the rock-shafts which constitute part of the operating mechanism thereof. This object I have accomplished by the means which are hereinafter 10 fully described and claimed, and which are illustrated in the accompanying drawings, in which:—

Figure 1 is a top plan view with the platform omitted, showing one end of a scale 20 embodying my invention; Fig. 2 is a detail plan view of the swinging link-connection for the rock-shaft; Fig. 3 is an end elevation of the same; Fig. 4 shows enlarged detail side and end elevations of the corner link; 25 and Fig. 5 is an enlarged detail of the rock-shaft end ring.

Similar reference numerals refer to similar parts throughout the several views.

My improvements are designed for use in 30 connection with that form of weighing-scales denominated commonly as "pitless" wagon-scales.

The numeral 1 designates a side wall of the scale frame, while 2 designates an end 35 thereof. Angle-plates 10 are fastened to the inside faces of each interior corner of the frame 1—2, and such plates are also provided with an upper horizontally projecting plate 18, of triangular shape. A cylindrical 40 stud 24 is secured to the inner face of one member of the angle-plate 10, at each corner of the frame, by means of a bolt passing through the side 1. Grooved rings 13 are mounted on the inner ends of the studs 24, 45 and links 12 are hung on said grooved rings so as to freely swing therefrom, as shown in Fig. 3.

The numeral 5 denotes a rock-shaft located parallel to and near the end-frames 2, 50 a similar shaft being located adjacent the other end-frame 2 (not shown), the ends of each rock-shaft having bearing arms 27 which rest in grooved rings 11 similar to the rings 13, and seated in the lower loops

of the links 12 so as to act as freely suspended bearings for the rock-shafts 5 aforesaid.

I have shown two longitudinal beams 3 and 4, each of which has secured to either end the plates 7, the latter extending beyond the ends of said beams and forming bifurcations having each a cross-piece 8 with a knife-edge on its lower surface, the knife-edge in each case bearing upon an inwardly projecting lug 9 of the rock-shafts 5. The 60 numeral 17 denotes arms projecting inwardly from said rock-shafts, secured to lugs on said rock-shafts. The operative connection of arms 17 to the scale-beam-lever may be of any ordinary or preferred sort 65 and is not shown because it forms no part 70 of the present invention.

The corner plates 18, while strengthening the connection at the corners of the frame, are useful also as a cover for the link-bearings thereunder, although the latter will always easily clear themselves from any deposit, by reason of their swing and rolling motion.

Having described my invention, what I 80 claim as new, and desire to secure by Letters Patent, is:—

1. In a weighing scale of the type set forth, the combination with a frame and a rock shaft, of a stud secured to the frame, a 85 grooved ring carried by said stud, a link having its upper end engaged about said ring, and a second grooved ring seated in the lower end of said link and rotatable with relation thereto, said shaft having a bearing 90 end for engagement in said second ring.

2. In a weighing scale of the type set forth, the combination with a frame and a rock shaft, of a link suspended for oscillating movement, and a grooved ring seated in 95 the lower end of said link and rotatable with relation thereto, said shaft having a bearing end for engagement in said ring.

3. In a weighing scale of the type set forth, the combination with a frame and a rock shaft, of a stud secured to the frame, a 100 grooved ring carried by said stud, a link having its upper end conformably engaged about said stud, and a second grooved ring conformably engaged in the lower end of 105 said link, said shaft having a bearing end for engagement in said second ring.

4. In a weighing scale of the type set

forth, the combination with a frame and a rock shaft, of a stud, a grooved ring carried thereby, and a link having its upper end conformably engaged about said ring, said link 5 being capable of oscillating movement with relation to said ring and supporting one end of said shaft.

Signed at Marshalltown, Iowa, this 27th day of April 1907.

DAVID LENNOX.
